UNITED STATES PATENT OFFICE.

ERNEST G. UNGER, OF NEW YORK, N. Y., ASSIGNOR TO KEEN WAVING COMPANY, INCORPORATED, OF NEW YORK, N. Y., A CORPORATION OF NEW YORK.

AUTOMATIC LOCKING CLAMP.

Application filed February 12, 1925. Serial No. 8,636.

The invention relates in general to a two jaw clamp of general application, and herein disclosed to be of a recessed jaw type particularly designed for clamping or crushing a 5 stiff paper tube into closed position incidental to practicing the art of permanent hair waving.

The primary object of the invention is to provide a form of clamp which can be easily 10 controlled and moved to and from its locking position by manipulation with the fingers of one hand.

Differently expressed an object of the invention is to provide a simplified form of 15 clamp which will feature two jaws pivotally connected so that in the movement of the jaws into clamping position they will be locked automatically against opening movement in the opposite direction and will be held in locking 20 position until positively unlocked by an overt act on the part of the operator simply by shifting the finger to a different part of the clamp.

All clamps of the type disclosed, employed 25 in the permanent hair waving art, are dependent upon the action of a spring as part of the locking mechanism. These springs quickly become rusty and the hot saline solutions employed in the art tend to cake on the 30 springs and other movable parts and seriously interfere with their ease of operation and of other life.

Accordingly another object of the invention is to provide a form of locking mechanism 35 which will reduce the movable parts to a single element, free of springs and other parts which might tend to collect the salts or other foreign matter.

Various other objects and advantages of 40 the invention will be in part obvious from an inspection of the accompanying drawings and in part will be more fully set forth in the following particular description of one form of device embodying my invention, and the 45 invention also consists in certain new and novel features of construction and combination of parts hereinafter set forth and claimed.

In the accompanying drawing:—

Figure 1 is a view in side elevation of a 50 strand of a person's hair contained in a cop tube used in the art of permanent hair waving and showing the end of the tube adjacent the person's head closed by means of a clamp

constituting a preferred embodiment of the 55 invention and shown in edge elevation;

Figure 2 is an enlarged transverse sectional view taken on the line 2—2 of Figure 1 looking in the direction indicated by the arrow and showing the clamp in side elevation; 60

Figures 3, 4 and 5 are detail views of the 65 three parts which go to make up the clamp; Figure 3 being a view of the jaw which carries the ratchet pin; Figure 4 being a view of the co-acting jaw which carries the ratchet and Figure 5 being a view of the ratchet.

In the drawings and referring first to Figures 1 and 2 there is shown a strand of hair "A" coiled on a tube "B" and contained within a stiff but crushable paper tube "C" all as 70 is well known in the art of permanent hair waving.

The inner end of the tube "C" adjacent the 75 person's head is closed by a clamp constituting the subject matter of this disclosure.

While the clamp is illustrated in its function of crushing a paper tube about a spiral winding of hair on a curling rod B, it is obvious that the clamp may be used as is usual with such devices to constitute a shield engaging the hair strand close to the scalp and between the same and the adjacent end of the curling rod.

The clamp comprises two co-acting jaws, 85 10 and 11, pivotally connected adjacent one end by means of a pivot pin 12. The jaws are somewhat U shaped and are each provided on their inner edges with a U-recessed edge 13. These recessed edges co-act when brought towards each other to crush the tube into engagement with the contained hair coil as 90 shown in Figure 2. The jaw 10 is provided adjacent its free edge with an outstanding finger engaging part of ear 14 and on one side face with a laterally extending ratchet pin 95 15. The co-acting jaw member 11 is offset from the plane of the jaw 10 so that the free end 17 is movable in a plane parallel to and offset from the side of the jaw 10 opposite the side from which the pin 15 projects. In this 100 way the free end 17 of the jaw 11 can move past the free end of the jaw 10 and lap the same as indicated in dotted lines in Figure 2. The jaw 11 has a bell crank shaped ratchet 18 pivoted thereto on a pivot pin 19. The 105 ratchet 18 conforms somewhat in configuration to that of the jaw 11, extends parallel to the same and is disposed so as to lap the side

of the jaw 10 from which projects the ratchet pin 15. The forwardly projecting arm of the ratchet is provided on its underside with a rack 19 of teeth inclined towards the pivotal axis of the pin 19. The rack is designed to be fed across the pin 15 and arranged so that one of the teeth forming the rack will be held by the pin against an opening movement in an anti-clockwise direction. A laterally extending stop pin 20 on the ratchet is designed to engage the outer edge 21 of the jaw 11 and thus limit the movement of the ratchet into its locking position engaging the pin 15. The outer edge of the ratchet 18 is provided with an outstanding ear 22 positioned on the side of the pivot 19 which contains the rack.

From this construction it will be understood that the operator's fingers engaging the outer sides of the ears 14 and 22 can pinch the same towards each other with the thumb and finger of one hand and thus move the jaws towards their closing position as shown in Figure 2. At the same time such movement will swing the rack into position to ride over the pin 15 and cause the same to successively engage the teeth of the rack. This movement is assisted by the rearward inclination of the rack teeth.

The opposite end of the ratchet is turned out of the general plane of the same to provide a laterally extending finger piece 23. The finger piece 23 laps the edge 21 of the jaw 11 and acts to limit the opening movement of the ratchet in disengaging the same from its locking connection with the pin 15.

In operation and assuming that the jaws are in a wide open U-position the clamp can be disposed in position to encircle the tube "C" or any other object which it is intended to clasp such for instance as the hair strand near the roots as was shown in connection with a different form of clip in my Patent No. 1,558,951, October 27, 1925. In this latter case the shield would be positioned intermediate the base of the lock of hair and the adjacent end of the curler. Pressure on the outstanding ears causes the jaws to move relative to each other about their pivotal connection and into desired clamping position with any desired degree of tension. At the same time the pressure on the ear 22 will swing the ratchet into its successive locking position engaging the pin 15. Releasing the tension on the ears will permit the pin to remain in position hooked by the last tooth which passed the same.

By shifting the finger or thumb into engagement with the finger piece 23 on the opposite side of the pivotal connection 19 the ratchet can be swung clear of its engagement with the pin 19 and the resiliency of the crushed tube will react on the jaws to open the same. Anyhow it is appreciated that the jaws may be otherwise opened and disengaged from the article clamped.

It is a feature of this disclosure that the parts can be made from simple stamping of sheer metal and the locking of the jaws is in no way dependent upon springs or other complicated forms of locking mechanism. In fact the construction can be designed without necessity of any refined machine operation and can be manufactured and placed on the market at low cost compared to similar devices now used.

No amount of pressure caused by expanding action of tube when clamp is once locked can force the clamp open.

Having thus described my invention, I claim:

1. A clamp for crushing a paste board tube towards a closed position, including a pair of jaws pivotally connected and having their opposed inner faces concaved to engage and crush opposite sides of the tube, a pin carried by one of the jaws and a ratchet pivotally connected to the other jaw and having one of its edges defined by a rack of teeth adapted to be moved into engagement with the pin to secure the jaws in this tube crushing position.

2. A clamp comprising a pair of jaws pivotally connected, a pin carried by one of the jaws, a ratchet pivoted to the other jaw, said ratchet provided on one side of its pivot and along its inner edge with ratchet teeth for engaging with said pin, said ratchet provided on the same side of its pivot with an ear for simultaneously swinging the ratchet teeth into engagement with the pin and for moving the jaw carrying the ratchet towards the jaw carrying the pin.

3. A clamp comprising a pair of jaws pivotally connected, a pin carried by one of the jaws, a ratchet pivoted to the other jaw, said ratchet provided on one side of its pivot with ratchet teeth for engaging with said pin, said ratchet provided on the same side of its pivot with an ear for simultaneously swinging the ratchet teeth into engagement with the pin and for moving the jaw carrying the ratchet towards the jaw carrying the pin, and means for limiting the movement of the ratchet towards the pin.

4. A clamp comprising a pair of jaws pivotally connected, a pin carried by one of the jaws, a ratchet pivoted to the other jaw, said ratchet provided on one side of its pivot with ratchet teeth for engaging with said pin, said ratchet provided on the same side of its pivot with an ear for simultaneously swinging the ratchet teeth into engagement with the pin and for moving the jaw carrying the ratchet towards the jaw carrying the pin and said ratchet provided on the other side of its pivot with a finger piece for moving the ratchet teeth out of engagement with the pin.

5. A clamp comprising a pair of jaws pivotally connected, a pin carried by one of

the jaws, a ratchet pivoted to the other jaw, said ratchet provided on one side of its pivot with ratchet teeth for engaging with said pin, said ratchet provided on the same side 5 of its pivot with an ear for simultaneously swinging the ratchet teeth into engagement with the pin and for moving the jaw carrying the ratchet towards the jaw carrying the pin, said ratchet provided on the other side of its 10 pivot with a finger piece for moving the ratchet teeth out of engagement with the pin, and said finger piece co-acting with its associated jaw for limiting the movement of the ratchet in disengaging itself from the pin.

15 6. In a clamp, the combination of a pair of jaws pivotally connected, one provided with an ear and with a pin, the other jaw having a ratchet pivotally mounted thereon and provided along one of its edges with ratchet teeth 20 for engaging the pin to secure the jaws, and a co-acting ear operatively connected to the ratchet whereby pressing the ears towards each other will close the jaws and automatically move the ratchet into holding engagement 25 with the pin.

7. In a device of the class described, the combination of a pair of members pivotally connected, a freely movable locking element pivoted intermediate its ends directly to one 30 of the members and provided adjacent one end with means adapted to engage the other member, and manually actuated means extending rigidly from said locking element in spaced relation to its ends, for swinging said 35 locking element.

8. In a clamp, the combination of a pair of jaws pivotally connected, one of said jaws provided with an ear and with one element of a jaw fastening means, the other jaw having 40 a coacting element of said fastening means pivotally mounted thereon and coacting with the first named element to secure the jaws in closed position, and a coacting ear forming part of said pivotally mounted element and 45 disposed so that in pressing the ears towards each other the jaws will close and the pivotal fastening means will be moved automatically into operative position.

9. A clamp including a pair of pivotally 50 connected jaws, one of which is provided with an outstanding ear constituting one of a pair of coacting finger pieces, a lever pivoted to the other jaw and provided with an outstanding ear constituting the other finger piece of said 55 coacting pair, said lever and the first named

jaw provided with a multiple position clamp for securing the jaw in a plurality of closed positions.

10. A clamp including a pair of coacting jaws, a pivot for connecting the same, a lever 60 pivotally mounted on one of the jaws for rotary movement about an axis of rotation fixed relative to said jaw and in spaced relation to said pivot, said lever provided with a tooth fixed relative to said axis of rotation and said other jaw provided with means adapted to be engaged by said tooth when moved with the pivoted lever into engagement thereunto, said tooth and means coacting to 65 secure the jaws in closed position.

11. A springless clip including a pair of pivotally connected jaws, means to lock said jaws in gripping position and a pair of radial handle members one connected to one of the jaws and the other connected to said locking 75 means, said handles movable relative to each other to release said locking means.

12. A clamp including a pair of pivotally connected jaws, and an arcuate tooth and ratchet connection between the jaws, said connection including a manually actuated member pivoted to one of the jaws and adapted to be moved to and from its engagement with the other jaw for holding the jaws in a plurality of positions and at points equidistant 80 from the pivotal connection of the jaws.

13. A clamp comprising a pair of jaws pivotally connected, a pin carried by one of the jaws, a ratchet pivoted to the other jaw, said ratchet provided on one side of its pivot 90 and along its inner edge with ratchet teeth for engaging with said pin, and means for swinging the ratchet to and from its position engaging the pin.

14. In a device of the class described, the combination of a pair of jaws pivotally connected, a progressively engaging locking means for securing the jaws in a plurality of closed positions, said means including a lever freely swinging pivoted to one of the jaws and provided with a finger piece constituting the sole means for swinging the same manually in one direction into an inoperative position disconnected from the other jaw and in the opposite direction into its succeeding operative positions engaging said other jaw.

Signed at New York in the county of New York and State of New York this 10th day of February, A. D. 1925.

ERNEST G. UNGER.
